CLAIM

The ornamental design for an electric pencil sharpener, as shown and described.

DESCRIPTION

FIG. 1 is a top, right front perspective view of an electric pencil sharpener showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.

FIG. 1

FIG. 2

FIG. 3

FIG. 5
FIG. 4

FIG. 6
FIG. 7
